Attorney

UNITED STATES PATENT OFFICE

RICHARD W. LUCE, OF MOUNTAINSIDE, NEW JERSEY, ASSIGNOR TO AMERICAN GAS-
ACCUMULATOR COMPANY, OF ELIZABETH, NEW JERSEY, A CORPORATION OF NEW
JERSEY

LIGHT-REFLECTOR SIGN AND SIGNAL

Application filed October 29, 1929. Serial No. 403,172.

My invention relates to light reflector signs and signals such for example as those used upon highways, streets and the like as traffic guides.

In the construction of such signs and signal devices it is the usual practice to embody in each device a plurality of reflector units and it not infrequently becomes necessary to repair the same by the substitution of a new reflector unit for an old one; or for some other reason it may become necessary to remove one or more units, less than the whole, hence it is desirable that each unit not only be supported independently of every other unit but also that the respective units may be readily removed.

The general object of the invention is to provide novel means of simple construction whereby each reflector unit of a group of units may be readily attached to and detached from its support, and whereby each unit may be supported independently of every other unit.

To the foregoing and other ends my invention comprehends the construction as herein-after described in detail, particularly pointed out in the claims appended hereto, and as shown in the drawing wherein I have illustrated one form of a convenient embodiment of the invention.

In the drawing:

Fig. 1 is a view in front elevation of a sign or signal device embodying the invention;

Fig. 2 is a transverse sectional view of a fragmentary portion of the device shown in Fig. 1 taken on the line 2-2 of said Fig. 1; and

Fig. 3 is a view in section of a support for a reflector unit, the said reflector unit being shown in spaced relation to its support and in position to be inserted into the holding means therefor.

In the drawing 1 designates a post or standard upon which is supported a plate

such as that shown at 2. The said plate is provided with a plurality of spring holding elements or devices 3 which are secured to and contiguously supported upon the plate 2 in separate groups or without regard to groups as may be desired. In the construction as illustrated they are arranged in separate groups, the units of each group being so related to each other as to form the letters S, T, O and P, spelling the word "Stop." In the construction as illustrated the spring holding elements 3 are provided with bottoms 4 which are secured to the plate 2 by spot welding, as indicated at 5, but may be otherwise secured thereto as by means of rivets or the like. Each of the reflector unit holding elements 3 is provided with oppositely disposed sides 6 which are curvilinear in cross section. These sides are convergent as shown so that the portions 7 thereof are nearer together than are the portions 8 which are located in adjoining relation to the bottom. The outer end portions of the sides are bent outwardly as indicated at 10 to provide the relatively widely separated portions 11 which are adapted to engage the outer enlarged end portion 12 of a reflector unit which is cylindrical in cross section. The inner end portion 13 of such unit is of smaller diameter than the portion 12 and engages with the portions of the sides 6 inwardly of the outer end portions 11. The connections between the portions 7 and 11 constitute shoulders against which the shoulder at 15 upon a reflector unit engages.

For the purpose of protecting and shielding the reflectors I have provided a protecting plate comprising a cover portion 20 having flanges 21 at its outer edges, the edges of which flanges are in contact with the plate 2. The protecting plate is secured upon the supporting plate 2 by means of fastening bolts 22. The portion 20 of the protecting plate is provided with openings 23 at intervals therein located in proper po-

sition to permit the front end portions of the respective reflector units of each group to project therethrough as indicated in Figs. 1 and 2 of the drawing. These openings are provided in raised portions 24 of the metal which are in the shape of letters as shown but may be of other shapes or configurations.

It will be apparent that upon the removal of the protecting plate the reflector units will be held securely in place by the spring holding elements 3 and that any one of said units may be removed without in any way disturbing any other of the said units.

It will be seen that by my invention I have provided means of simple construction whereby a reflector unit may be removably held upon a support therefor and whereby each unit of a group of units may be removed without disturbing in any respect whatsoever any one of the other units of such group.

Having thus described my invention, what I claim and desire to secure by Letters Patent is:

1. A device of the character described comprising a supporting plate, a plurality of spring holding elements secured to said plate, each of said elements having oppositely disposed spring sides, light reflector units mounted in the said spring holding elements and held by the said oppositely disposed sides thereof, and a protecting plate mounted upon the first named plate and having openings which register with the said reflector units.

2. A device of the character described comprising a supporting member, spring holding elements mounted upon said member, said spring holding elements respectively comprising oppositely disposed sides which are convergent and which are curvilinear in cross section, light reflector units removably mounted within said spring holding elements, the said units being circular in cross section, a protecting plate removably mounted upon the said member and having openings in registry with the respective light reflector units.

3. A device of the character described comprising a supporting member, spring holding elements mounted upon the said member, said elements respectively comprising oppositely disposed sides which are convergently related, said sides having inner and outer end portions, the latter portions being bent laterally outward to form shoulders intermediate the inner and outer end portions, and light reflector units mounted between the said sides and removably held in place thereby.

4. A device of the character described comprising a supporting member, spring holding elements mounted upon the said member, said elements respectively compris-

ing oppositely disposed sides which are convergently related, said sides having inner and outer end portions, the latter being bent laterally outward to form shoulders intermediate the inner and outer end portions, and the said sides being curvilinear in cross section, and light reflector units mounted between the said sides and removably held in place thereby, the said units being cylindrical in cross section.

In testimony that I claim the foregoing as my invention I have hereunto signed my name this 25th day of October, A. D. 1929.

RICHARD W. LUCE.
